(57) **CLAIM**

The ornamental design for a stainless steel insulated cup, as shown and described.

DESCRIPTION

FIG. 1 is a front, right, top perspective view of a stainless steel insulated cup in the first state, showing my new design; FIG. 2 is a rear, left, bottom perspective view thereof; FIG. 3 is a front elevational view of the reduced scale thereof;

FIG. 4 is a rear elevational view of the reduced scale thereof; FIG. 5 is a left side view of the reduced scale thereof; FIG. 6 is a right side view of the reduced scale thereof; FIG. 7 is a top plan view of the reduced scale thereof; FIG. 8 is a bottom plan view of the reduced scale thereof; FIG. 9 is an enlarged view of detail 9 in FIG. 1; and, FIG. 10 is a front, right, top perspective view of a stainless steel insulated cup in the second state.

The dashed broken lines in the figures illustrate portions of the stainless steel insulated cup that form no part of the claimed design.

The dash-dot-dash broken lines are for notating enlarged views and form no part of the claimed design.
